UNITED STATES PATENT OFFICE.

LUTHER D. LOVEKIN, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

OIL-BURNING SYSTEM.

1,094,078.

Specification of Letters Patent. Patented Apr. 21, 1914.

Application filed April 1, 1911. Serial No. 618,411.

To all whom it may concern:

Be it known that I, LUTHER D. LOVEKIN, a citizen of the United States of America, residing in Philadelphia, county of Philadelphia, and State of Pennsylvania, have invented certain new and useful Improvements in Oil-Burning Systems, of which the following is a true and exact description, reference being had to the accompanying drawings, which form a part thereof.

My present invention relates to oil burning apparatus and particularly to oil burning apparatus of the kind in which the oil, substantially free from any admixture with steam or air, issues in the form of sprays or jets from the burner nozzles to which it is supplied under high pressure.

With apparatus of this type as heretofore constructed it has been found possible to obtain high efficiency, but the best results have, in practice been obtained only when the apparatus was very carefully designed and received constant and careful attention and adjustment. This has been due, I believe, to the character of apparatus heretofore employed to supply the oil to the burners.

The object of my present invention is to provide apparatus for the purpose specified which is inherently simpler and more effective and reliable and adapted to give better average efficiency and to require less care and attention than that heretofore employed. This I accomplish in large measure by using centrifugal pumps in place of the reciprocating pumps heretofore used for forcing the oil into the burner nozzles. The advantages obtained by this change in the pumping mechanism are due, I believe, to certain inherent but more or less obscure conditions not heretofore fully understood or appreciated, but which may be explained as follows: To obtain efficient and satisfactory operation it is essential that the air for supporting the combustion of the oil sprayed from the burner nozzles be continuously supplied in amount exactly regulated to the amount of oil issuing from the burner nozzles at any instant, and it is essential in practice also that the sprays or jets of oil issuing from the burner nozzles do not fluctuate. When the rate at which the oil is sprayed from each burner nozzle does not vary, it is a comparatively simple matter to properly regulate the supply of the air sup-

porting combustion, but fluctuations in the pressure of the oil supplied to the burner nozzles, and consequently in the rate at which the oil is sprayed therefrom, not only directly interferes with the operation of the apparatus by producing variations in the amount of oil consumed and irregularities and disturbances in combustion, but also disturbs the instantaneous ratio between the amount of oil being burned and the amount of air supplied for its combustion. In consequence of these and other considerations, pulsations in the pressure at which the oil is supplied to the burner nozzles produces miniature explosions and flarebacks which reduce the efficiency of the apparatus and makes the operation of the apparatus hazardous and arduous.

Heretofore the oil has been supplied to the burner nozzles, at the high pressure required for what is known as "mechanical atomization" by reciprocating oil pumps. The intermittent manner in which reciprocating pumps discharge the fluid pumped by them tends to produce substantial fluctuations in the pressure in the conduit connections between the pumps and burner nozzles. In order to equalize the pressure in the oil supply connections between the pump and the burners it has heretofore been the practice to employ air chambers. I have found, however, that centrifugal pumps give more uniform pressure conditions in the oil connections running to the burners than it is possible to obtain with reciprocating pumps, and any arrangement of air reservoirs which it is feasible to employ under most conditions and particularly on warships where oil burning apparatus is of peculiar utility and where efficiency, reliability and space economy are all prime requisites.

The use of air reservoirs is objectionable, not only because of the space occupied by the reservoirs themselves, but also because it is necessary to provide space occupying and energy consuming means for constantly replenishing them with air. Under the pressure at which the oil is supplied to the burner nozzles, the oil possesses a capacity for absorbing or dissolving substantial amounts of air, especially, since for satisfactory results the oil must be highly heated before being supplied to the burners. This absorption of the air by the oil, occurring when air chambers are used is objectionable,

not only because of the consequent necessity for continuously replenishing the air chambers but also, the variable mixture of air and oil in the pressure supply system, is in itself undesirable. For one thing there is always a possibility though a remote one of the formation of an explosive mixture in the conduit system under some conditions occasionally experienced.

10 In the accompanying drawing and descriptive matter I have illustrated and described a preferred form of oil burning apparatus embodying the present invention.

Of the drawings, Figure 1 is an elevation of a portion of a boiler furnace and apparatus for feeding oil to the burners thereof. Fig. 2 is a partial sectional elevation of the apparatus shown in Fig. 1. Fig. 3 is a plan view, and Fig. 4 a side elevation of a 15 turbine driven centrifugal pump employed in the apparatus shown in Fig. 1, and Fig. 5 is a diagrammatic representation of the oil burning system.

In the drawings, A, represents a water tube boiler furnace of conventional type.

25 B is an oil burner nozzle and B' a register regulating the admission of air to the interior of the boiler furnace through ports surrounding the burner nozzle. Each 30 burner nozzle is supplied with oil through its individual pipe C from the main C', the latter is connected at its supply end to two filter chambers D, D. The latter are supplied with oil through the pipe C² from the 35 outlet of the two oil heaters E, E. The oil is passed directly to the oil heaters E, E, through the pipe C³ from the discharge pipe C⁴ of two centrifugal pumps F, each driven by a suitable motor, which, as shown, 40 is a steam turbine FA. The suction or inlet passages of the pumps F are connected through the pipe C⁵ to the preliminary filters G, G, and the latter in turn are connected by the pipe C⁶ to the oil reservoir H.

45 O, represents a steam supply pipe having branches O' running to the oil heaters E, E, the turbines FA, FA, and heating coils O² arranged within the oil reservoir H. P, represents drain pipe connection for the 50 water of condensation formed in the heaters E, E, and coil O², and Q, represents a trap for discharging the water of condensation. P, represents a return line or bypass through which a circulation may be advantageously had at times when the plant is 55 being started up.

It will be understood that in the system shown, the pumps, filters and heaters are provided in duplicate to increase the reliability of the apparatus, since this permits parts to be cut out one at a time when neces-

sary for cleaning or repairs. This duplication while desirable is not strictly essential.

Those skilled in the art will understand that the apparatus disclosed, while of a desirable and preferred form is illustrative merely. The gist of the invention consists not in the particular form or arrangement of apparatus disclosed, but primarily in the use of a centrifugal pump for forcing the 70 oil under pressure into the burner nozzles, and secondarily in the employment of a conduit connection between the pump and the burners which is entirely filled with oil in normal operation, and which I may describe as non-elastic to distinguish it from conduit connections including air chambers in which the confined air forms an elastic wall portion of the connecting conduit system. For the full utilization of the benefits 75 of the invention I find it desirable also to provide means, which may advantageously be of the form shown, for preliminarily heating the oil passing to the pump or pumps and for then further heating the oil 80 in its passage from the pump or pumps to the burners. By proceeding in this manner I am able to readily give the oil the high temperature desirable without subjecting the pump to unduly high temperatures. In 85 practice the pressure at which the oil is forced into the burner nozzles is practically never below sixty pounds and ordinarily ranges between 100 and 250 pounds per square inch and the temperature of the oil 90 is preferably between 200 and 250 degrees 95 Fahrenheit.

Having now described my invention, what I claim as new and desire to secure by Letters Patent, is:

100

1. In an oil burning system the combination with the burner nozzles of means for supplying them with heated oil under atomizing pressure, comprising a centrifugal pump and a closed conduit system connecting said pump to said burner nozzles and entirely filled with oil in normal operation.

105

2. In an oil burning system the combination with the burner nozzles of means for supplying them with heated oil under atomizing pressure, comprising a centrifugal pump and a closed conduit system connecting said pump to said burner nozzles, and including heating provisions for the oil passing from the pump to the nozzles 110 through said system and entirely filled with oil in normal operation.

115

LUTHER D. LOVEKIN.
